UNITED STATES PATENT OFFICE.

JOHN C. FORSTER, OF PITTSBURGH, PENNSYLVANIA.

GARNISHING-TOOL.

1,266,672.

Specification of Letters Patent. Patented May 21, 1918.

Application filed December 9, 1916. Serial No. 135,988.

To all whom it may concern:

Be it known that I, JOHN C. FORSTER, a citizen of the United States, and resident of Pittsburgh, in the county of Allegheny and State of Pennsylvania, have invented certain new and useful Improvements in Garnishing-Tools, of which the following is a specification.

The object of this invention is to provide a household tool of improved construction for cutting vegetables, fruits, etc., in fluted slices, the invention having particular reference to the arrangement of the handle with reference to the blade for strengthening the latter and at the same time so located as to not obstruct the view of the tool necessary for directing its slicing strokes.

In the accompanying drawings Figure 1 is a perspective view of the preferred embodiment of the invention. Fig. 2 is a cross-section thereof on line 2—2 of Fig. 1. Fig. 3 is an elevation of the implement showing a handle of modified form.

Referring to the drawings, 2 designates a blade of thin or sheet metal which is formed with a series of vertical parallel flute-like corrugations 3 which extend from top to bottom thereof. The blade is of substantial depth, and by preference its horizontal dimension exceeds its height. The lower or cutting edge 4 of the blade is preferably inclined with relation to its top edge to produce a shearing effect and thereby facilitate the slicing operation.

35 The handle consists of two shank-like portions 5 and 6, each formed with an angularly bent extremity 7 and these extremities are embraced by or secured in the end flutes or corrugations 3' of the blade. Shank portions 5 and 6 project horizontally from one side of the blade, with portion 5 extended across and above the blade and parallel with its top edge as indicated at 5' in order to reach the distant portion of the blade to 45 which it is secured. The elongated shank 5 and the relatively short shank 6 merge into the grip forming loop 8, in the construction

shown in Fig. 1, the handle elements thus being formed of a single piece of stout wire. With portion 5' above and paralleling the top edge of the blade, the latter is materially strengthened or stiffened throughout its horizontal dimension, and at the same time the handle or grip is located at one side of the blade and out of the way of the slicing operation and also out of the line of vision in directing the blade through the article being sliced.

In the construction shown in Fig. 3, a wooden handle-grip 9 of conventional form is substituted for grip 8, and when this form of handle is employed the shank portions 5 and 6 are simply projected thereinto a distance sufficient to obtain the requisite hold.

I claim:

1. A slicing knife consisting of an approximately straight thin sheet metal blade transversely fluted from end to end with the flutes extending from one longitudinal edge to the other, and a handle projecting in line with said blade and beyond an upper corner thereof and provided with a stiffening member extending the entire length of said blade and at its outer end bent so as to lie within the extreme outer flute of said blade, said handle also being provided with an angular member lying within the inner flute of said blade.

2. A slicing knife consisting of a sheet metal blade transversely corrugated to form a longitudinally fluted cutting edge, and a handle projecting in line with said blade beyond an upper corner thereof and at right angles to the corrugations of the blade; said handle being provided with blade securing portions standing at right angles to the major axis of the handle and secured within the extreme outer corrugations of the blade.

In testimony whereof I affix my signature in presence of two witnesses.

JOHN C. FORSTER.
